UNITED STATES PATENT OFFICE

REX G. HAMAKER, OF HOUSTON, TEXAS, ASSIGNOR TO REED ROLLER BIT COMPANY,
OF HOUSTON, TEXAS, A CORPORATION OF TEXAS

CORE CATCHER

Application filed April 1, 1929. Serial No. 351,688.

This invention relates to well drilling apparatus, and more particularly to core catchers for core drills.

There are two types of core catchers now 5 in common use—that adapted to hold a hard formation core, and that adapted to hold a soft formation core. And if a core drill equipped with a hard formation core catcher passes through soft formation, the soft formation 10 core will not be held, and vice versa.

This invention has for one of its objects the provision of a new and improved core catcher adapted to hold both hard and soft formation cores.

15 Another object is to provide a new and improved core engaging spring finger mounting.

In the accompanying drawings Fig. 1 is a top plan view of the preferred embodiment 20 of the core catcher; Fig. 2, a sectional elevation thereof; Fig. 3, a fragmentary sectional elevation of a core drill equipped with a core catcher and holding a soft formation core; and Fig. 4, a view similar to Fig. 3, illustrating the holding of a hard formation core.

As shown particularly by Figs. 1 and 2, the preferred embodiment of the core catcher includes a plurality of short spring fingers 1, and a plurality of long spring fingers 2, 25 carried by the rings 3 and 4.

The inner ring 3 is externally beveled, and the outer ring 4 is internally beveled to form upwardly and inwardly inclined meeting faces, indicated at 5, the spring fingers 1 and 35 2 being held therebetween. The rings are preferably welded at the bottom as indicated at 6.

It will be obvious to those skilled in the art that the rings 3 and 4, welded together 40 at the bottom, provide a strong and rigid support for the spring fingers without weakening them. The boring of rivet holes and injudicious welding has heretofore produced 45 weakened fingers incapable of withstanding the strains to which they are necessarily subjected in deep well core drilling operations.

When a core drill equipped with my new and improved core catcher passes through 50 any formation, both the long and short

spring fingers will move out of the path of the inwardly moving core.

When a soft formation has been drilled, and the drill is elevated, the long fingers 1 will move inwardly to hold the soft formation core 7 within the core barrel 8, as illustrated by Fig. 3. The short fingers may be so disposed that, in that event, they will move inwardly to assist the long fingers.

It is a difficult, if not impossible, matter 60 to construct a core catcher having relatively long fingers capable of holding a soft formation core and also satisfactorily adapted to sustain a hard formation core, the latter of which may comprise solid rock of sufficient 65 weight to bend and break long fingers. On the other hand short fingers, while incapable of holding very soft formation cores, possesses great strength and are capable of sustaining heavy hard cores.

Now when the drill is elevated after penetrating a hard formation, the strong and relatively short fingers 1 of my core catcher move inwardly into engagement with the hard core 9, as illustrated by Fig. 4; and 70 firmly support the same in the core barrel 8.

It will be apparent from the foregoing that my new and improved core catcher comprises few parts characterized by simplicity and strength, and adapted to hold either a hard 80 or a soft formation core.

My invention is not limited to the specific embodiment shown.

Various changes may be made within the scope of the following claims.

I claim:

1. A core catcher having core engaging fingers and a pair of supporting rings, said fingers being held between said rings, and extending upwardly, said rings being welded 90 together at the bottom.

2. A core catcher having core engaging fingers and a pair of supporting rings, the meeting faces of said rings being inclined upwardly and inwardly, and said fingers being 95 held between said rings.

3. A core drill having a core barrel, and a core catcher within said barrel, said catcher having upwardly and inwardly presented, long and short, core engaging fingers, said 100

long fingers being of a length greater than the radius of said barrel.

4. A core drill having a core barrel, and a core catcher within said barrel, said catcher having upwardly and inwardly presented, long and short, core engaging fingers, said long fingers being of a length greater than the radius of said barrel, and said short fingers being substantially one-half as long as

10 said long fingers.

5. A core catcher having a ring, long and short fingers carried by said ring and inclined toward the axis of said ring, said long fingers being of a length greater than the radius of said ring.

15 In testimony whereof, I hereunto affix my signature.

REX G. HAMAKER.
